UNITED STATES PATENT OFFICE.

SAMUEL B. COOKE, OF RICHMOND, VIRGINIA.

CAN OPENER.

Application filed March 10, 1927. Serial No. 174,283.

This invention relates to can openers and has for an important object thereof the provision of a device of this character capable of use with cans of varying sizes and which 5 includes means whereby the knife and can are held in fixed relation to one another without the application of force by the user.

A further object of the invention is to produce a device of this character having a construction such that the perforation of the 10 can by the blade is greatly facilitated.

A further object of the invention is to provide a device of this character which may be readily and cheaply produced and which 15 will be durable and efficient in service.

These and other objects I attain by the construction shown in the accompanying drawings, wherein for the purpose of illustration is shown a preferred embodiment of my invention and wherein:—

Figure 1 is a side elevation of a can opener constructed in accordance with my invention, a can being indicated in dotted position thereon;

Figure 2 is a vertical sectional view therethrough, a can likewise being shown in dotted position;

Figure 3 is a section on the line 3—3 of Figure 1;

Referring now more particularly to the drawings, the numeral 10 indicates a standard having at its upper and lower ends flanges 11 and 12. The flange 12 has its free end reverted at 13 and the end of the revert 35 has a downwardly deflected portion 14 abutting the flange 12 in spaced relation to the standard. The space between the adjacent faces of the downwardly deflected portion 14 is adapted to receive the rim R of a can and the 40 revert acts to prevent outward movement of the rim from the standard 10. The flange 11 merely forms a limit, preventing separation from the standard of the mechanism hereinafter described.

Slidable upon the standard 10 is a yoke 15, the end walls 16 of which fit closely against the side edges of the standard. This standard has an extension 17 to which, at a point adjacent the free end, a handle 18 is pivotally connected and the end of the handle 18 is folded upon itself, as at 19, to increase the size of the hand grip provided therefor. This handle has secured thereto a blade 20 which, when the handle is horizontally disposed, approximately aligns with the standard. The forward edge 21 of this blade or that edge

next adjacent the pivot 21, by which the handle is secured to the extension 17, is sharpened, as is the bottom edge 22 thereof. This bottom edge connects with the forward edge 23 in a manner providing a piercing point 23. The end of the handle 18 which is connected to the pivot 21 is extended slightly beyond this pivot and sharpened, as at 22.

In the use of the can opener, the yoke 15 and handle are slid to the upper end of the standard and the can placed so that its bottom rim is held between the standard and the revert 13, as hereinbefore described. The yoke and handle are then slid downwardly, the handle being at an angle to the yoke, as indicated in Figure 1. With the yoke adjacent the top of the can, the hand grip 19 is forced downwardly. At this time, the point 23 will act as a pivot upon which the handle 18 will tend to rock as a lever, so that the pivot 21 would be elevated. This causes a slight canting of the yoke 17, with the result that this yoke locks upon the support and any further pressure applied to the handle will tend to force the point 23 and cutting edges 21 and 22 into the can top. After the blade has been forced into the can top, the can may be rotated with the hand until the top is completely severed. In order to maintain the blade and handle more nearly in alignment with the circumference of the can, this blade is preferably slightly arcuately curved, as shown more clearly in Figure 3. The point 22 may be conveniently employed in removing bottle caps or for removing can tops that have been depressed into the can and are difficult of access.

It will be obvious that a device of this character may likewise be conveniently employed for punching can tops, the contents of which are to be poured from the can. Since the construction hereinbefore set forth is capable of a certain range of change and modification without materially departing from the spirit of the invention, I do not limit myself to such specific structure except as hereinafter claimed.

I claim:—

1. In a can opener of the type described, a standard, means at the lower end of the standard and coacting therewith for maintaining a can rim in fixed position with relation to the standard during rotation of the can, a yoke slidable upon the support, a handle pivoted adjacent one end to the yoke, said yoke locking upon the standard upon

the application of pressure thereto tending to tilt the same, the connection of the handle with the yoke being in spaced relation to the standard and a can top cutting blade 5 secured to the handle intermediate the free end and pivot thereof.

2. In a can opener of the type described, a standard comprising a bar having an angular flange at its lower end, said flange having a revert the end of which is spaced from the standard a distance such as to permit insertion of a can rim therebetween, a yoke 10

slidable upon the standard and when canted with relation thereto gripping the standard, a handle having at one end a hand grip and 15 having pivotal engagement with the yoke whereby upward pressure upon the pivotal connection causes canting of the yoke and a can top cutting knife carried by said handle between the pivot and hand grip thereof. 20

In testimony whereof I hereunto affix my signature.

SAMUEL B. COOKE.
